UNITED STATES PATENT OFFICE.

WILLARD JONES, OF AUBURN, MAINE.

CURTAIN-BRACKET.

No. 845,420.

Specification of Letters Patent.

Patented Feb. 26, 1907.

Application filed April 26, 1906. Serial No. 313,857.

To all whom it may concern:

Be it known that I, WILLARD JONES, a citizen of the United States, residing at Auburn, in the county of Androscoggin and State of Maine, have invented a new and useful Curtain-Bracket, of which the following is a specification.

This invention relates to brackets for holding window-shade rollers and curtain-poles, and it is more particularly an improvement upon the bracket described and claimed in Patent No. 795,704 granted to me on July 25, 1905.

The object of the invention is to form in one piece a base-plate and its supporting-arms, a shade-roller bracket, and a suitably-braced guide.

A still further object is to provide a curtain-pole support which is adjustably mounted on the guide and can be moved from or toward the base-plate at will.

With the above and other objects in view the invention consists of a base-plate having angular arms extending from its upper ends and provided with spurs for engaging the top of a window-frame. The metal removed in the formation of these arms is utilized as a guide which extends at right angles from the base-plate and terminates in a brace which is suitably fastened to the base-plate. A shade-roller bracket extends from the base-plate and is formed of material struck therefrom. A pole-supporting bracket is slidably mounted on the guide and has integral means for engaging the same, so as to prevent displacement of the guide.

The invention also consists of certain other novel features of construction and combinations of parts, which will be hereinafter more fully described and pointed out in the claims.

In the accompanying drawings I have shown the preferred form of my invention.

In said drawings, Figure 1 is a perspective view of the complete device. Fig. 2 is a similar view of the slide and pole bracket, the ears being shown in the position before and after bending by full and dotted lines, respectively.

Referring to the figures by numerals of reference, 1 is a base-plate of suitable contour having a shade-roller bracket 2, projecting at

right angles from the lower portion thereof, said bracket being formed by striking it from the base-plate and twisting it, as at 3, so as to bring the apertured end thereof into alignment with the longitudinal center of the base-plate. Diverging arms 4 extend from one end of the base-plate and terminate in extensions 5, extending at right angles thereto and provided with depending spurs or prongs 6, substantially parallel to the arms 4. An elongated strip is formed of the metal removed from between the arms 4, and this strip is bent at right angles to the base-plate to form a guide 7, which terminates at its outer end in a brace 8, the free end of which is soldered or otherwise permanently connected to the base-plate and preferably at the inner end of the bracket 2. A slide 9 is mounted on the guide 7 and has oppositely-disposed ears 10, which embrace the guide and hold the slide against displacement. This slide has a hook 11 at one end for receiving a curtain-pole, and said hook may be provided with any suitable means, as a screw 12, for holding the pole within it.

It will be noticed that by constructing a combination-bracket in the manner here described it consists of two pieces, the base-plate with its arms, a shade-roller bracket and guide-brace, all being adapted to be stamped from a single sheet of metal. By providing the device with a braced guide such as shown and described the pole-receiving hook 11 can be readily adjusted away from or toward the base-plate to satisfy different conditions and tests.

What is claimed is—

1. A combination-bracket comprising a base, pronged supporting-arms integral therewith, a roller-shade bracket struck from said base, a guide extending at right angles to and integral with the base, said guide terminating at its outer end in a brace permanently secured to the base, said base and the parts integral therewith being formed in a single sheet of metal, and a pole-bracket adjustably mounted upon the guide.

2. A combination-bracket formed in two pieces one of said pieces comprising a base, angularly-pronged arms at one end of the base, a guide extending from between the arms and terminating in a brace, and a shade-

roller bracket extending from the base, said brace being permanently connected to the base adjacent the bracket, and the other piece comprising a hooked slide and oppositely-disposed ears integral therewith and embracing the guide.

In testimony that I claim the foregoing as

my own I have hereto affixed my signature in the presence of two witnesses.

WILLARD JONES.
